CLAIM

The ornamental design for a fragrance bottle, substantially as shown and described.

DESCRIPTION

FIG. 1 is a top, front, right side perspective view of a first embodiment of a fragrance bottle showing my new design;

FIG. 2 is a front elevational view thereof; a rear elevational view being a mirror image thereof;

FIG. 3 is a right side elevational view thereof; a left side elevational view being a mirror image thereof;

FIG. 4 is a top plan view thereof;

FIG. 5 is a bottom plan view thereof;

FIG. 6 is a top, front, right side perspective view of a second embodiment of a fragrance bottle showing my new design;

FIG. 7 is a front elevational view thereof; a rear elevational view being a mirror image thereof;

FIG. 8 is a right side elevational view thereof; a left side elevational view being a mirror image thereof;

FIG. 9 is a top plan view thereof; and,

FIG. 10 is a bottom plan view thereof.
